UNITED STATES PATENT OFFICE.

JOSEPH W. ROY, OF DETROIT, MICHIGAN, ASSIGNOR OF FIFTY-ONE ONE-HUNDREDTHS
TO PHILEAS DELAGE, OF DETROIT, MICHIGAN.

VALVE-SEAT GRINDER.

Application filed April 16, 1925. Serial No. 23,529.

My invention relates to a new and useful improvement in a valve seat grinder and has for its object the provision in a valve seat grinder of means adapted for engaging a valve stem guide for centering the grinder 5 relatively to the valve seat.

Another object of the invention is the provision in a valve seat grinder of a centering member having a grinding member held at an inclination thereto, the angle of inclination 10 of the grinding member being adjustable relatively to the centering member.

Another object of the invention is the provision in a valve seat grinder of a centering member which may be expanded to various 15 lengths.

Another object of the invention is the provision of a valve seat grinder having a centering member adapted for carrying the 20 grinding member at an inclination thereto, the angle of inclination being variable and the distance of the grinding member from the centering member being adjustable.

Other objects will appear hereinafter.

The invention consists in the combination 25 and arrangement of parts hereinafter described and claimed.

The invention will be best understood by reference to the accompanying drawings 30 which form a part of this specification and in which,

Fig. 1 is a vertical central sectional view of the invention.

Fig. 2 is a sectional view taken on substantially line 2—2 of Fig. 1.

Fig. 3 is a sectional view taken on substantially line 3—3 of Fig. 1.

As shown in the drawings the invention 40 is adapted for use with internal combustion engines in which a valve 9 is adapted to seat on the valve seat 10. The valve 9 is provided with a valve stem 10' adapted for passing through a guide sleeve 11. The invention is designed for providing means for 45 grinding the valve seat 10 and is particularly efficient in grinding the valve seat 10 concentrically of the guide sleeve 11, so that the valve 9 may securely seat on its seat throughout its seating surface. The invention 50 comprises a tubular member 12 which is interiorly threaded and provided with a flange 13 at one end and a flange 14 at the other end. Threaded into the tube 12 is a stem 15 having a bore 16 formed in its lower 55 end, the lower end being provided with a

flange 17 adapted when the device is in operative position for engaging the upper end of the sleeve 11. Projecting from one side of the tube 12 are concentrically arranged arcuate arms 18 and 19, these arms being struck from a center contained within the longitudinal axis of the stem 15. An inferiorly threaded sleeve 18' is provided with a pair of bosses 22 each having an opening 20 formed therein for the reception of one 60 of the arms 18 or 19. A set screw 21 is threaded into the boss 22 adapted to engage the arcuate arm 18 or 19 so as to fix the position of the sleeve 18' relatively to the position of the sleeve 12. It is evident that the 65 sleeve 18' is always inclined to the longitudinal axis of the sleeve 12 and that this angle of inclination may be varied depending upon the position of the sleeve 18' relatively to the arms 18 and 19. Threaded into the sleeve 18' is a tubular member 23 through which is projected a shaft 24 having its upper end threaded as at 25 for the reception of the suitable coupling 26 which is secured to the flexible shaft 27. The lower end 70 of the shaft 24 is reduced and provided with a collar 28 which engages the collar 29. Mounted upon the reduced portion 28 is a suitable grinding wheel 30 which is adapted for rotating in unison with the shaft 24. 75 The structure is such that upon a rotating of the flexible shaft 27 by an electric motor or other suitable power device, the grinder 30 will be caused to rotate. Threaded into the lower end of the bore 16 is a stem 31 80 which has an outwardly projecting portion 32 adapted for engaging in the bore 33 of the sleeve 11.

In operation the device is placed in the position shown in Fig. 1 so that the stem 32 engages in the bore 33 and serves to center the device relatively to the valve seat 10. The angle of inclination of the sleeve 18' relatively to the sleeve 12 is then fixed, this angle being determined by the inclination of the surfaces of the valve seat 10. The pipe 12 and the member 15 are adjusted longitudinally to the desired length depending upon the length of the sleeve 11.

The tube 23 may be also adjusted longitudinally of the sleeve 18'. When the proper adjustment has been made to these parts, the lock nuts 34 and 35 are tightened.

When the shaft 27 is set in rotation, the tube 12 carrying with it the tube 18', may 110

be manually rotated by the operator grasping the upper end of the stem 15. In this way, the grinder 30 is properly centered relatively to the valve seat 10 and its angle of 5 inclination adjusted to a very fine degree so that the valve seat may be accurately and quickly ground from a true center and with proper inclination.

It is believed that the durability and simplicity of the various parts is apparent and that the ease with which these parts may be 10 adjusted is evident.

While I have illustrated and described the preferred form of structure, I do not wish 15 to limit myself to the precise form of structure shown, but desire to avail myself of such variations and modifications as come within the scope of the appended claims.

Having thus described my invention, what 20 I claim as new and desire to secure by Letters Patent is:

1. A valve seat grinder of the class described, comprising a center pin; a supporting member having a socket for the reception 25 of said center pin; a sleeve threaded on said supporting member and adapted for threading longitudinally thereof; arcuate arms projecting outwardly from said sleeve; a tubular member adjustably carried by said 30 arcuate arms; a grinding member; and means for carrying said grinding member mounted in said sleeve on said arms for regulating the distance of said grinding member from said center pin.

2. A valve seat grinder adapted for grinding a valve seat having a tubular valve stem guide projecting axially thereof, comprising a guide stem, adapted for insertion into said valve stem guide; a supporting member; a 40 grinding member carried by said supporting member at an inclination to said center pin, the angle of inclination being variable at will, said supporting member being longitudinally adjustable relatively to said center pin for regulating the position of said grinder relatively to the end of said center pin.

3. A valve seat grinder of the class described, comprising a center pin, adapted 45 for insertion into a valve stem guide; a shaft

having a socket for the reception of one end of said center pin; a sleeve threaded on said shaft; a pair of arms projecting outwardly from said sleeve, said arms being arcuate; a grinding member supported on said arms 55 and movable circumferentially of said arms for varying the inclination of said grinding member relatively to said stem, said sleeve being adjustable longitudinally of said shaft for varying the distance between the end of 60 said pin and said grinding member.

4. A valve seat grinder adapted for grinding a valve seat having a tubular valve stem guide projecting axially thereof, comprising: a guide stem adapted for insertion into said 65 valve stem guide; a supporting member; a grinding member carried by said supporting member at an inclination to said guide stem, the angle of inclination being variable at will; and adjustable means for adjusting the 70 position of said grinding member at various distances from the end of said guide stem.

5. A valve seat grinder adapted for grinding a valve seat having a tubular valve stem guide projecting axially thereof, comprising: a guide stem adapted for insertion into said valve stem guide; a supporting member carried by said guide stem; a grinding member carried by said supporting member at an inclination to said guide stem, the angle 75 of inclination being variable at will; adjustable means, longitudinally movable of said supporting member for engaging the upper end of said valve stem guide.

6. A valve seat grinder adapted for grinding a valve seat having a tubular valve stem guide projecting axially thereof, comprising: a guide stem adapted for insertion into said valve stem guide; a supporting member carried by said guide stem; a grinding member; means for supporting said grinding member on said supporting member at an inclination to said guide stem, the angle of inclination being variable at will; and means for moving said grinding member axially 90 relatively to said guide stem.

In testimony whereof, I have signed the foregoing specification.

JOSEPH W. ROY.
